DESIGN FOR A GOLF TEE

Leo Reifman, Jackson Heights, N. Y.

Application October 12, 1946, Serial No. 133,911

Term of patent 14 years

(Cl. D34—5)

To all whom it may concern:

Be it known that I, Leo Reifman, a citizen of the United States, residing in the city of Jackson Heights, county of Queens, State of New York, have invented a new, original, and ornamental Design for Golf Tee, of which the following is a specification, reference being had to the accompanying drawing, forming a part thereof, in which:

Fig. 1 is a side elevational view of my new design for a golf tee;

Fig. 2 is a side elevational view of said golf tee taken at right angles to the view of Fig. 1, and

Fig. 3 is a bottom plan view thereof.

The dominant feature of my design resides in the combination on the tee disclosed of a pin extending through one of a pair of transverse openings in the body portion, in association with a cap on the tip portion having a pair of arms ris-

ing therefrom and engaging the shank on the sides opposite the transverse pin, as shown.

I claim:

The ornamental design for a golf tee, as shown and described.

LEO REIFMAN.
